UNITED STATES PATENT OFFICE.

HARPER E. STRATTON, OF EMPIRE, OHIO, ASSIGNEE OF ONE-HALF TO C. M. STRATTON,
OF TORONTO, OHIO.

GEAR-WHEEL.

995,387.

Specification of Letters Patent. Patented June 13, 1911.

Application filed December 8, 1910. Serial No. 596,342.

To all whom it may concern:

Be it known that I, HARPER E. STRATTON, a citizen of the United States of America, and resident of Empire, county of Jefferson, and State of Ohio, have invented certain new and useful Improvements in Gear-Wheels, of which the following is a specification.

This invention relates to gear-wheels, and more particularly to a wheel of the type mentioned having a separable rim or crown.

The primary object of the invention is to provide a two-part gear wheel in which the rim or crown is readily detachable from the wheel-body rendering said parts interchangeable and adapting the wheel-body for having different sizes of rims or crowns applied thereto.

A further object is to provide a gear-wheel which may be quickly and conveniently transformed from one working size to another by the mere interchange of rims or crowns and without the removal of the wheel-body or hub from the shaft on which it is mounted.

With these and other objects in view, the invention consists in the particular construction, arrangement and combination of parts which will hereinafter be fully described, reference being had to the accompanying drawing, forming a part of this specification, in which—

Figure 1 is an inner side elevation of a gear wheel of the bevel-gear type constructed in accordance with my invention, a portion of the gear rim being broken away; Fig. 2 is an outer side elevation of the same, a portion of the wheel body being shown broken away; and Fig. 3 is an enlarged section on the line 3—3, Fig. 1.

In said drawing, like designating characters distinguish like parts throughout the several views.

The body of the wheel consists of a spider composed of a hub 1 and a plurality of integral radial arms 2, the latter being preferably webbed to an appropriate distance from the hub, as shown, for affording increased strength. An integral rib 3 is formed on the inner face of each arm 2, which rib projects outward beyond the end of the arm and constitutes an extension 4. A lug 5 is formed on the side of said extension 4 adjacent to the end of the arm 2, and a second lug 6 is formed on said exten-

sion at its extreme end, said lugs being formed with their inner faces flush with the corresponding face of the extension and having bolt-holes therethrough. Each of the extensions 4 are offset to form shoulders 7 behind the position of the lug 5, said shoulders being adapted to abut the inner ends of angular arms 8 formed integral with, and on the reverse face of, a toothed gear rim or crown 9 fitted against the inner faces of said extensions. Said arms 8 are shaped to substantially correspond with the extensions 4 and are adapted to rest flat against the latter, having their opposite ends projected beyond the inner and outer peripheries 70 of the rim. Bolt-holes are provided in the opposite ends of said arms 8 for registering with the holes in the extensions, and bolts 10 are projected through the registering holes for rigidly connecting the rim or 75 crown to the spider.

From the foregoing it will be seen that I provide a gear-wheel which may be readily transformed from one size to another by the mere removal of the rim or crown and the 80 substitution of another of the desired size.

As is obvious, rims of spur-gear and other types may be employed as readily as may the bevel-gear type depicted in the figures 85 of the drawing.

It will be apparent that the invention is readily susceptible of various mere mechanical changes or alterations in the form and arrangement of its parts and within the scope of the appended claims.

Having thus described my invention, what I claim as new, and desire to secure by Letters Patent, is—

1. A gear wheel comprising a hub having radial arms provided with shouldered extensions, a toothed gear rim having a plurality of integral arms formed on one side thereof, said arms being seated on said extensions, the last mentioned arms having their opposite ends projected beyond the inner and outer peripheries of said rim, and bolts connecting the last mentioned arms to said extensions, said bolts being located beyond the inner and outer edges, respectively, of said rim.

2. A gear wheel comprising a hub having radial arms formed with integral ribs on the inner faces thereof, said ribs projecting beyond the ends of said arms to constitute extensions which are offset to form shoulders,

a circular toothed gear rim having integral arms on its reverse face seated on said extensions, the last mentioned arms corresponding in size and form with said extensions and having their opposite ends extended beyond the inner and outer peripheries of said rim, with their inner ends seated against said shoulders, and bolts rigidly connecting the last mentioned arms to said extensions,

one of said bolts being located inside the inner periphery and the other outside the outer periphery of said rim.

In testimony whereof I affix my signature in presence of two subscribing witnesses.

HARPER E. STRATTON.
